Primary Examiner — Shannon W Morgan*Assistant Examiner* — Terilyn Davis(57) **CLAIM**

The ornamental design for a coffee rack, as shown and described.

DESCRIPTION

FIG. 1 is a top perspective view of a coffee rack showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 in FIG. 1.

The broken lines show the features of the coffee rack that form no part of the claimed design. The dash-dot-dash broken lines define the boundary of an enlarged view and form no part of the claimed design.
